UNITED STATES PATENT OFFICE.

MOSE DON EAST, OF SEATTLE, WASHINGTON, ASSIGNOR TO Z SYSTEM CONSTRUCTION INC., OF SEATTLE, WASHINGTON, A CORPORATION OF WASHINGTON.

STORAGE BUILDING.

Application filed November 7, 1925. Serial No. 67,579.

My invention relates to improvements in storage buildings the objects of which are to provide means whereby a greater floor area can be obtained for a given site area than with buildings of regular construction, and also to provide means whereby cars or trucks may drive up to or down from any floor by easy gradients, and that the direction taken when driving both up or down shall be the same so that the danger of cars colliding is eliminated.

The invention consists essentially of an arrangement whereby each floor overlaps in part the floor below, and inclined runways extend from one floor to the overlapping portion of the floor above and to the overlapping portion of the floor below, as will be more fully shown in the following specification, in which:

Fig. 1 is a fractionated floor plan.

Fig. 2 is a sectional view taken on the line 2—2 of Figure 1.

Fig. 3 is a sectional view taken on the line 3—3 of Figure 1.

Fig. 4 is a plan of a floor of a building as adapted for a site of small dimensions.

Fig. 5 is a plan of an alternate floor of a building as shown in Figure 4.

In the drawings like characters of reference indicate corresponding parts in each figure.

The numeral 1 indicates a pair of side walls and 2 a pair of end walls to the building. The numeral 3 indicates a main floor area extending between the end walls 2 and along the side wall 1 on opposite sides of the building, and 4 are floor spaces extending between the portions 3 along the end walls 2, all of the floors being supported on suitable columns 5. The numeral 6 indicates floor spaces which extend inwards from the areas 3 towards the centre of the building. Runways 7 and 8 extend between the floors, all of which are adapted to be traversed in the same direction, those indicated by the numeral 7 leading to the floor above and those indicated by the numeral 8 leading to the floor below. The numeral 9 indicates a further floor area extending between

the areas 6 and 3 and the inner ends of all the runways 7 and 8. In the storage of motor vehicles low storey heights are sufficient to house private cars, taxicabs, and busses, but greater storey height is required for trucks and vans. Similarly for the

storage of heavy goods low storeys are suitable and high storeys are required for the storage of light or bulky goods. Therefore, by arranging my building to provide for two tiers of floor areas 4 and 6 to each tier of areas 3 and 9 I provide ample accommodation of requisite ceiling height for all requirements and increase the effective floor area of my building without increasing its total height.

It will also be noted that as each set of runways 7 and 8 being required to reach to a vertical height only equal to the distance between the areas 3 and 9 or one half of the storey height of such areas, that the gradients are relatively slight and can be traversed either up or down by any loaded vehicle without danger. The runways being arranged in pairs with one leading to an upper floor and the other to a lower floor, enables all cars to travel in the same direction so that danger from collision is eliminated.

In the modification, the numeral 10, see Figure 4, indicates floor areas extending between the end walls 2 along the side walls 1 and reaching towards the centre of the building to surround on three sides the runways 7 and 8, and 11 is a further floor area connecting the areas 10 together. The numeral 12, see Figure 5, indicates a floor area extending inwards from the end walls 2 and reaching outwards to the runways 7 and 8. The numeral 13 indicates an opposing pair of areas, and 14 is a central floor area. The areas 13 and 14 are of the low storey height and the areas 12 are of high storey height, therefore a similar added area of floor space is attained as is shown in Figures 1, 2, and 3 over the regular type of construction.

What I claim as my invention is:

1. A storage building having a plurality of floors disposed at half story intervals one above the other, alternate floors being constructed to extend the full overall width of the building and being provided with centrally disposed openings having the marginal portions thereof spaced a considerable distance inwardly from the enclosing walls of the building whereby each of said floors affords a storage area entirely surrounding the opening formed therein, the remaining floors being arranged with their central portions opposite said openings and with the edges thereof projecting beyond and in

spaced overlapping relation to the floor edges defining said openings, said remaining floors being extended between two opposite enclosing walls of the building and being spaced from the remaining opposite walls of the building.

2. A storage building having a plurality of floors disposed at half story intervals one above the other, alternate floors being constructed to extend the full overall width of the building and being provided with central openings spaced inwardly and appreciable distance from the enclosing walls of the building, the remaining floors being positioned opposite said openings with their edges extending beyond and overlapping the floor edges defining said openings to provide additional storage space between the overlapping portions of said floors and ramps interconnecting adjacent floors.

3. A storage building having a plurality of floors disposed at half story intervals one above the other, alternate floors being con-

structed to extend the full overall width of the building and being provided with central openings spaced inwardly a considerable distance from the enclosing walls of the building, the remaining floors being extended between two opposite enclosing walls of the building and spaced from the remaining enclosing walls of the building, said remaining floors being arranged with their central portions opposite said openings and their edges projecting beyond and overlapping the adjacent floor edges defining said openings and ramps interconnecting the overlapping portions of adjacent floors, there being two pairs of ramps provided at each of two opposite sides of said openings, the ramps of each pair being respectively arranged to connect one floor with the adjacent upper and lower floors.

Dated at Vancouver, B. C., this 23rd day of October, 1925.

MOSE DON EAST.
